UNITED STATES PATENT OFFICE.

IVAN C. BELL, OF DALLAS, TEXAS.

WRENCH.

Application filed June 20, 1924. Serial No. 721,371.

This invention relates to new and useful improvements in wrenches.

The object of the invention is to provide a wrench having a plurality of gripping members substantially equally spaced so that in gripping a tubular member, the latter is engaged at a number of points, thus minimizing crushing.

Another object is to provide two pairs of grips arranged so that the work is initially gripped by diametrically opposite grips, and the other grips brought into engagement with the work as the wrench is tightened thereon, thus reducing slipping and assuring a firm bite, as well as applying equal pressure at the points of gripping.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is an elevation of the jaw portions of a wrench constructed in accordance with my invention, the parts being in initial gripping position.

Fig. 2 is a vertical sectional view of the same, the wrench having been tightened on the work.

Fig. 3 is a sectional view on the line 3—3 of Fig. 1, and

Figs. 4 and 5 are details of modified forms of grips.

In the drawings the numeral 10 designates a handle having at its upper end a rigid jaw 11 extended laterally to overhang the handle. Immediately below the jaw the handle depends through a yoke 12 which is fulcrumed on a bolt 13 extending the handle near its inner edge. The handle has a boss or enlargement 14 under the jaw opposite the bolt 13. A horizontal recess 15 is made in the boss, relatively below the bolt for receiving a coiled spring 16. The spring has its outer end engaging the yoke for holding the latter in position on the handle.

A movable jaw 17 overhangs the jaw 11 and has an integral shank 18 depending therefrom at substantially right angles thereto. The shank has screw threads 19 and passes through spaced ears 20 extending from the yoke. A milled circular nut 21 engaged on the shank is confined between the ears and by rotating said nut the shank is

displaced longitudinally of the handle and the jaw 17 moved toward or from the jaw 11, as is usual in this type of wrench.

A gripping die or block 22 is mounted in the forward portion of the lower jaw 11 which has a recess or cavity 22' for receiving said die. A similar die 23 is mounted in a recess 23' in the inner or rear part of the said jaw. The upper jaw has a cavity 26 in its under side, and receives outer and inner dies 24 and 25 respectively. Each die referred to is circular in form and has ratchet teeth on its periphery directed in a counter-clockwise direction.

Each die is removably mounted but held against rotation by a polygonal tubular bolt 27 passing through the center of the die and its respective jaw and held in place by a machine screw 28. The openings in the dies as well as in the respective jaw snugly receive the bolts 27, so that said dies cannot rotate on the bolts nor can the bolts rotate in the openings of the jaws. By this arrangement when a section of teeth become worn the bolt 27 may be removed, the die rotated sufficiently to bring a new section of teeth into use, and the bolt replaced. In Fig. 4 I have shown octagonal form of die 29 and in Fig. 5 a square form of die 30. Any suitable form may be used.

It will be seen that four dies are employed to grip the work. The inner die 23 may be mounted a short distance above the outer die 22. Thus when the wrench is applied to the work A the die 22 will more readily swing past the work so that the die 23 may initially engage the work. In applying the wrench the inner die 23 of the lower jaw 11 and the outer die 24 of the upper jaw are initially engaged with the work A at substantially diametrically opposite points as is shown in Fig. 1. When the handle 10 is swung in a counter-clockwise direction the dies are moved relatively around the work to bring the other dies 22 and 25 into gripping engagement therewith, the four dies taking "bites" at substantially equidistant points and applying approximately equal pressure.

It will be seen that the initial slippage will be taken up by the dies 23 and 24 and when the following dies 22 and 25 are brought into contact with the work, the slippage will be stopped and a firm grip will be taken. The provision for adjusting the dies circumferentially makes for long life and a gener-

ous supply of sharp teeth. The wrench is adjusted and used in the same manner as other wrenches of this type.

Various changes in the size and shape of the different parts, as well as modifications and alterations may be made within the scope of the appended claims.

What I claim, is:

1. In a wrench, the combination of an upper jaw, a pair of spaced dies having circumferential teeth and being circumferentially adjustable in the upper jaw, a lower jaw, a second pair of dies having circumferential teeth and being circumferentially adjustable in the lower jaw, and means for fastening all the dies against rotation.
2. In a wrench, the combination of an upper jaw and a lower jaw, and dies mounted in opposed relation in said jaws each having teeth on their peripheries, all dies being adjustable circumferentially to present new teeth when those in use become worn, said dies being fastened against rotation.
3. In a wrench, the combination of an upper jaw, a pair of spaced dies having circumferential teeth and being circumferentially adjustable in the upper jaw, a lower jaw, a second pair of dies having circumferential teeth and being circumferentially adjustable in the lower jaw, and means for fastening all the dies against rotation, the dies being so related that a single upper and a single lower die initially engage the work and the remaining dies subsequently engage the work.

4. In a wrench, the combination of an upper jaw and a lower jaw pivoted to swing relatively of the upper jaw, and a plurality of dies mounted in opposed relation in both the jaws, some of said dies being located in the jaws so as to initially grip opposite sides of the work fully received in the jaws, and the remainder of said dies being located so as to subsequently grip another portion of the work when the lower jaw is swung, the first named dies substantially retaining their initial gripping engagement.

5. In a wrench, the combination of an upper jaw and a lower jaw, and dies held against rotation and positioned in the jaws so that diametrically opposite dies initially engage the work and additional dies are brought into engagement with the work as the jaws are rotated relatively of the work.

6. In a wrench, the combination of a handle, a lower jaw mounted on the end of the handle, said lower jaw being recessed, an upper jaw having its underside recessed and overhanging the lower jaw, a yoke on the handle in which the upper jaw is adjustable, a pair of spaced toothed dies mounted in the recessed portion of the lower jaw, and a second pair of spaced toothed dies mounted in the recessed portion of the upper jaw over the first pair of dies, said dies being circumferentially adjustable.

In testimony whereof I affix my signature.

IVAN C. BELL.
